UNITED STATES PATENT OFFICE.

ANTON C. EGGERS, OF BROOKLYN, NEW YORK, ASSIGNOR TO THE GOODYEAR'S INDIA RUBBER GLOVE MANUFACTURING CO., A CORPORATION OF CONNECTICUT.

CLOSURE FOR CONTAINERS.

1,183,962.

Specification of Letters Patent. Patented May 23, 1916.

Application filed September 28, 1915. Serial No. 52,934.

To all whom it may concern:

Be it known that I, ANTON C. EGGERS, a citizen of the United States, residing in Brooklyn, county of Kings, and State of New York, have invented certain new and useful Improvements in Closures for Containers, of which the following is a full, clear, and exact description.

This invention relates to closures for containers more especially of that general class formed of rubber such as water bottles, ice bags, ice caps, etc.

An object of the present invention is to provide a closure through which the container may be filled and emptied without contact of the contents with metallic members so that the annoying corrosion with consequent poor fitting of the usual metallic closures will be positively obviated.

A further object is to provide a closure which will be normally maintained closed by straight resilient members which may be readily compressed between the forefinger and thumb of an operating hand to assume bowed form and open the closure.

A still further object is to provide a closure which is practically flat in normal form and may be rolled upon itself and fastened in small compact form and when in such form will effectively seal the container while at the same time will be comfortable to the person using the same.

The invention can be readily understood from the following description taken in connection with the accompanying drawing in which;

Figure 1 is a front elevation of a container embodying my improvements; Fig. 2 is an enlarged longitudinal sectional view 40 through the closure showing the same in open position in dotted lines; Fig. 3 is a perspective view showing the closure in condition to seal the container; Fig. 4 is a fragmentary sectional view showing a modified form of resilient member for the closure.

Referring now to the drawing which illustrates one embodiment of the invention, 10 designates a container such as an ice bag, formed of rubber in the usual and well known manner, the neck 11 of the bag being a continuation of the flat side walls of the bag.

In carrying out the invention I provide a closure for the neck of the bag comprising 55 a tube 12 which is preferably formed of the

same rubber material as the bag. A pair of resilient members 13 are arranged on opposite sides of the tube, in the present embodiment each comprising a cylindrical rubber case 14 which is cemented or otherwise secured to the tube and within which is housed a helical spring 15. The helical springs are straight in normal condition and when compressed from this normal position by pressure exerted upon the ends by placing the same between the thumb and forefinger of the hand, the springs are readily bowed and coact in forming a circle thereby carrying the walls of the tube to this circular form so that the bag may be filled or emptied through the open tube as desired. The resilient members are preferably secured at such distance from the neck of the bottle that the tube 12 may be rolled upon itself over the resilient members into a small compact roll as shown, and the closure is confined in this rolled condition by two flaps 16 and 17 secured to the neck of the bottle and having their free ends connected by clasps 18 which hold the strips 80 tightly encircled upon the rolled closure.

Instead of employing helical springs in the resilient members I may employ simply hard rubber cores 19 which act in the same manner as the springs and may secure the cores to the sides of the tube 12 in any preferred manner. I may furthermore make other changes in the construction illustrated without departing from the spirit or sacrificing any of the advantages of the invention.

It will be seen that the above described construction is devoid of metal parts that might contact with the contents of the bag so that the annoyances of corrosion with consequent poor fitting attendant upon metal closures in articles of this character is positively obviated. It will further be seen that the rolled closure forms an effective seal which prevents leakage of the contents of the bottle while at the same time the small compact form of the rolled closure will be comfortable to the person using the bag.

What I claim and desire to protect by Letters Patent is:

1. The combination with a container of a closure of tubular form, resilient members normally holding said closure in flat condition and adapted to be bowed outwardly to

open the closure, said closure being rollable upon said members to form a roll which effectively seals the container, and means for holding said closure in rolled condition.

5 2. The combination with a container of a closure of tubular form, straight resilient members normally holding said closure in flat form and adapted to be bowed outwardly to open the closure, said closure being rollable upon said members to form a

small compact roll which seals said container, and flaps carried by the container and adapted to be encircled over the rolled closure and hold the same in rolled condition.

15

Signed at New York, county and State of New York, this 27th day of September, 1915.

ANTON C. EGGERS.
